PAPER WINDING MECHANISM

Application filed September 12, 1929. Serial No. 392,001.

This invention relates to paper winding mechanisms.

In most paper mills, the paper comes in a continuous sheet from the machine and is wound on a roll or reel. Consequently, a winding mechanism is desired which will receive the paper continuously and permit rapid change of winding from a full roll to an empty or fresh roll so that there is little or no loss of paper in changing from one roll to the next.

One form of winding mechanism embodies a rotating drum driven at a uniform speed the same as, or slightly faster than, that of the oncoming sheet which contacts with the drum periphery and is driven thereby. In the usual form of this mechanism, a plurality of rolls are removably mounted adjacent the drum with one roll in a winding position and another out of winding position, but adapted to be brought into such position when the first roll is filled and ready to be removed.

It is the object of this invention to improve such mechanisms, to make the construction more simple and practical, and render the operation more reliable and dependable. The invention embraces improved means for supporting and moving the winding rolls out of and into winding position, and includes mechanism for adjusting the positions of the rolls and aligning them.

The invention further consists in certain features, combinations, arrangements and details of construction which will first be described in connection with the accompanying drawings and then more particularly pointed out in the claims.

In the drawings,—

Figure 1 is a side elevational view of a winding mechanism constructed in accordance with the invention, with one roll omitted but indicated in dotted lines;

Figure 2 is a plan view of this mechanism;

Figure 3 is a front elevation of the mechanism.

The embodiment chosen to illustrate the invention comprises a rotatable drum 10 which, as here shown, is mounted on a horizontal shaft 11 journaled in bearings 12 carried by standards 13 resting on the floor or

other horizontal surface. The drum is intended to be rotated at a uniform speed the same as, or slightly faster than, that of the oncoming sheet. The rotating means illustrated as an example involve a belt-driven cone pulley 14 having a shaft 15 aligned with shaft 11 and connected thereto at one end by a suitable coupling 16 and journaled at the other end in a bearing 17 carried by a floor standard 18. The embodiment further includes a plurality of rolls, in this case, two rolls 19, having shafts 20 projecting from each side of each roll and positioned horizontally in parallelism with shaft 11 of the drum. The paper is wound on one of these rolls, that shown to the right in Figure 1, which is in contact with the drum, while the other roll is out of winding position at the left and out of contact with the rotatable drum.

Means are provided for removably journaling the rolls. As here shown, the rolls are movably journaled in bearings 21 open at the top to permit entrance or removal of the projecting shaft ends of the rolls. The shafts 20 are equipped with collars 22 which abut against the sides of the bearings, when the shafts are placed therein, to insure proper axial disposition of the rolls.

The invention in its entirety involves means for movably supporting the roll bearings whereby a roll may be moved out of winding position and another roll moved into winding position. Although capable of various constructions, in that here shown as an example, the roll bearings are removably positioned on parallel supporting members 23 in the form of beams and may be moved on said members and adjusted. As here shown, the members are carried and pivoted on the free ends of links or levers 24, as by pins 25. The left hand links (Figure 1) are pivoted at their lower ends 26 to standards 13, the right hand links fixed on an auxiliary shaft 27 which is arranged parallel the axes of the drum and rolls and journaled in standards 13. The links are advantageously of equal length so that the supporting members keep their same inclinations.

Means are present for rotating the links on

their pivots to move the supporting members. The mechanism chosen for illustration comprises a hand wheel 28 having a shaft 29 and a worm 30 on said shaft meshing with a gear 31 fixed on a shaft 32 carried and journaled in a standard 13. Shaft 32 has gear 33 meshing with gear 34 free on shaft 27. Rotation of gear 34 is communicated to shaft 27 through a connection embodying a ratchet wheel 35 fixed to shaft 27 and meshing with spring-pressed pawls 36 on the side of gear 34.

Means are provided for shifting the positions of the roll bearings on the supporting members. In the construction shown, the supporting members house elongated screws 37 extending throughout their lengths and meshing with half-nuts 38 on the undersides of the roll bearings (Figure 3). One of said screws has a hand wheel 39 for rotating it. The screws may be connected by a cross shaft 40 through bevel gears 41. The cross shaft is advantageously housed in a casing 42. Provision is made for moving the cross shaft into and out of connecting position and, to this end, a shifting cam 43 or similar mechanism for moving the shaft may be provided. Usually, the cam is thrown to connect the screws and to cause simultaneous movement of all the bearings. If, however, the winding roll is out of alignment or parallelism with the rotatable drum, this can be remedied by throwing the cam to disconnect the screws and by running the bearings on one supporting member only until alignment is achieved.

In operation, the paper coming from the paper machine on the left (Figure 1) goes under a spreader 44, which is advantageously adjustable, over the rotatable drum and is wound on the right hand roll into a paper roll of the desired size. In this winding action, the supporting members are free to rise as the paper roll builds up to larger and larger diameter, the weight of the paper roll holding it in contact with the rotating drum. When the roll is of the desired size, it is swung away from the rotating drum by action of the hand wheels, while the empty roll is brought into contact with the drum and winding now continues on this roll. The completed roll is then removed from the machine, and by manipulation of the hand wheels the new roll is brought into the position formerly occupied by the full roll, the empty bearings of the removed roll being first removed and later put in the former position of the new roll so as to receive another empty roll. The insertion of a new empty roll does not, therefore, interfere with the winding operation.

The roll being wound may be easily placed in contact with the rotating drum at different points and at any desired point by the manipulations of the hand wheels. As the roll builds up and its weight increases, the links

move into a more nearly vertical position and take up more and more of the weight, thus relieving the drum of the additional weight due to increase in the roll. The pressure of the paper roll on the drum is thus practically constant, in spite of the increased size and weight of the roll.

What is claimed is:

1. In a winding mechanism, a rotatable drum, means for rotating the drum at a uniform speed, means for supporting a plurality of winding rolls whereby one roll is in winding position and another roll is out of winding position in relation to said drum, said supporting means including a pair of movable frames supported to maintain a parallel position with each other throughout their range of movement, said frames at the same time being free to move correspondingly with the changing relative position of the winding roll to the rotating drum due to the increasing diameter of the winding roll.

2. In a winding mechanism, a rotatable drum, means for rotating the drum at a uniform speed, supporting members on which a plurality of winding rolls are removably carried, said supporting members including a pair of parallel frames pivotally supported at a plurality of points so as to maintain a parallel relation one with the other throughout their range of movement, and means for moving the supporting members to withdraw a roll from winding position and move a roll to winding position in relation to said drum, said supporting members maintaining their inclinations during movement.

3. In a winding mechanism, a rotatable drum, means for rotating the drum at a uniform speed, means for supporting a plurality of winding rolls whereby one roll is in winding position and another roll is out of winding position in relation to said drum, said supporting means including a pair of movable frames supported to maintain a parallel relation with each other throughout their range of movement and at the same time are free to move correspondingly with the changing relative position of the winding roll and the rotating drum due to the increasing diameter of the winding roll, and means for shifting the positions of the rolls along the supporting members.

4. In a winding mechanism, a rotatable drum, means for rotating the drum at a uniform speed, means for supporting a plurality of winding rolls whereby one roll is in winding position and another roll is out of winding position in relation to said drum, said supporting means including a pair of pivoted parallel frames and a plurality of sliding supports carried thereby in which the winding rolls are supported, means for moving the supports along the frames simultaneously, and means for effecting an independent ad-

- justment of each end of a winding roll to align it with the axis of the rotatable drum.
5. In a winding mechanism, a rotatable drum, means for rotating the drum at a uniform speed, supporting members, open-top bearings carried by said members and in which winding rolls are removably journaled, one roll being in winding position while another roll is out of winding position in relation to said drum, a pair of pivoted links carrying each supporting member, and means for rotating the links on their pivots to move a roll from winding position and another roll into winding position.
- 10 6. In a winding mechanism, a rotatable drum, means for rotating the drum at a uniform speed, supporting members, open-top bearings carried by said members and in which winding rolls are removably journaled, one roll being in winding position while another roll is out of winding position in relation to said drum, means for shifting the positions of said bearings along the supporting members for aligning the bearings with the axis of the rotatable drum, and means for moving the supporting members to withdraw a roll from winding position and move a roll to winding position in relation to said drum.
- 15 7. In a winding mechanism, a rotatable drum, means for rotating the drum at a uniform speed, supporting members, open-top bearings carried by said members and in which winding rolls are removably journaled, one roll being in winding position while another roll is out of winding position in relation to said drum, means for moving the supporting members to withdraw a roll from winding position and move a roll to winding position in relation to said drum, screws associated with the supporting members for shifting the bearings, means for rotating one of said screws, a connecting shaft geared to the screws, and means for throwing said shaft into and out of geared connection with the screws.
- 20 8. In a winding mechanism, a rotatable drum, means for rotating the drum at a uniform speed, supporting members, open-top bearings carried by said members and in which winding rolls are removably journaled, one roll being in winding position and another roll out of winding position in relation to said drum, means for moving the supporting members to withdraw a roll from winding position and move a roll to winding position in relation to said drum, screws associated with the supporting members for shifting the bearings, means for rotating one of said screws, and means for connecting and disconnecting the screws.
- 25 9. In a winding mechanism, a rotatable drum, means for rotating the drum at a uniform speed, supporting members on which a plurality of rolls are removably carried, one roll being in winding position and another
- roll out of winding position in relation to said drum, a pair of pivoted links carrying each supporting member, said links being of equal length, and means for rotating said links on their pivots to move a roll from winding position and another roll into winding position.
- 30 10. In a winding mechanism, a rotatable drum, means for driving the drum, supporting members on which a plurality of rolls are removably carried, one roll being in winding position and another roll out of winding position in relation to said drum, a pair of pivoted links carrying each supporting member, said links being of equal length but pivoted in different horizontal planes so that the supporting members are inclined, and means for rotating said links on their pivots to move a roll from winding position and another roll into winding position.
- 35 11. In a winding mechanism, a rotatable drum, means for rotating the drum at a uniform speed, a pair of parallel frames capacitated to carry a plurality of roll supports so arranged that one roll is in winding position and another roll out of winding position in relation to said drum, a pair of pivoted links carrying each support member, and means for rotating said links on their pivots to move a roll from winding position and another roll into winding position.
- 40 12. In a winding mechanism, a rotatable drum, means for rotating the drum, a pair of parallel frames capacitated to so support a plurality of winding rolls that one roll is in winding position and another roll is out of winding position in relation to said drum, a pair of screws for moving the winding rolls, means for connecting the screws so as to move both ends of a winding roll simultaneously, and means for rendering the connecting means inoperative so that each end of a winding roll may be separately adjusted.
- 45 In witness whereof, we have hereunto set our hands.
- CHARLES W. VALENTINE.
